Application September 14, 1955, Serial No. 534,281

21 Claims. (Cl. 222—70)

This invention relates to a filling machine and more particularly to a gravity type liquid filling machine.

The invention has for an object to provide a novel and improved filling machine of the character specified wherein novel provision is made for controlling the flow of the liquid into the containers in a manner such as to provide uniform quantities of liquid in successive containers in a simple, rapid and efficient manner.

A further object of the invention is to provide a novel and improved filling machine of the character specified having a liquid control valve of novel structure adapted to accurately control the flow of liquid into the containers and to prevent dripping of liquid from the discharge nozzle upon completion of the filling operation.

With these general objects in view and such others as may hereinafter appear, the invention consists in the filling machine and in the various structures, arrangements and combinations of parts hereinafter described and particularly defined in the claims at the end of this specification.

Referring now to the drawings:

Fig. 1 is a rear view of a filling machine embodying the present invention;

Fig. 2 is a side elevation of the machine;

Fig. 3 is a detail view of an elevator operated control valve to be referred to;

Fig. 4 is a detail view partly in cross section of a rotary valve forming a part of the control mechanism;

Fig. 5 is a perspective view diagrammatically illustrating a portion of the rotary valve in one position of operation;

Fig. 6 is a view similar to Fig. 5 showing the valve in a different position of operation;

Fig. 7 is a cross sectional view of a filling head showing the liquid control valve in its open position;

Fig. 8 is a view similar to Fig. 7 showing the valve in its closed position;

Fig. 9 is a cross sectional detail view of a portion of the filling head showing a different discharge nozzle;

Fig. 10 is a cross sectional view of an air cylinder forming a part of the present control mechanism to be referred to;

Fig. 11 is a view similar to Fig. 10 showing the air cylinder in a different position of operation;

Fig. 12 is a detail view partly in cross section showing the control valve between the source of supply and the liquid supply tank;

Fig. 13 is a detail view partly in cross section showing a portion of the control mechanism for maintaining a uniform filling level in the liquid supply tank;

Fig. 14 is a piping diagram illustrating the various pneumatic controls for operating the liquid control valve and liquid level control mechanism;

Fig. 15 is a side elevation of a control cam partly in cross section as viewed from the line 15—15 in Fig. 1;

Fig. 16 is a detail view in side elevation as seen from the line 16—16 in Fig. 1 illustrating a portion of the one revolution clutch and control therefor; and

Fig. 17 is a similar view as seen from the line 17—17 in Fig. 1 and showing a different portion of the one revolution clutch.

In general in its preferred form the present invention 5 contemplates a novel and improved liquid filling machine of the gravity type wherein provision is made for accurately controlling the quantity of liquid introduced into successive containers and which embodies a filling head having a novel liquid control valve wherein both opening 10 and closing motions are positively and accurately controlled, the closing movement of the valve being preferably performed gradually to taper off the flow through the valve and discharge nozzle and to thereafter create a slight suction in the discharge end of the nozzle for the purpose of preventing dripping from the nozzle when the filling operation is completed. In the illustrated embodiment of the invention the filling head is provided with a chamber having a liquid inlet at one side thereof and a depending discharge nozzle. The liquid control valve comprises a vertically movable member which may extend through the chamber and through a reduced diameter opening formed immediately below the chamber, the cylindrical wall of which forms a seating area for the movable valve member extended therethrough. The movable valve member may be entirely 20 of resilient material or, as herein shown, may be provided with a resilient ring at its outer periphery for engagement with the seating area which latter may be slightly smaller in diameter than the outside diameter of the resilient portion of the vertically movable valve member. In operation, movement of the valve member downwardly out of engagement with the wall of the seating opening permits passage of liquid through the discharge nozzle and into the container to be filled, and as 25 the liquid flowing into the container approaches a predetermined filling height or level in the container, the movable valve member is gradually elevated through novel timing mechanism to be described to present the resilient portion of the valve member into engagement with the cylindrical wall of the reduced diameter seating opening whereby to effect slight compression of the resilient member to cut off the flow of liquid. In practice during such gradual closing of the valve the flow of liquid 30 through the nozzle is gradually reduced whereby a minimum of disturbance of the liquid is effected when approaching the filling height in the container, and thereafter a slight continued upward movement of the valve member effects a slight suction to retain the column of liquid remaining below the valve member within the nozzle whereby to prevent dripping therefrom at the end of the filling operation.

In accordance with another feature of the present invention provision is made for maintaining a uniform hydrostatic head of liquid in the supply tank whereby to 35 maintain a uniform pressure for controlling the flow of liquid through the filling head. In the illustrated embodiment of the invention novel float actuated and pneumatically controlled mechanism is preferably employed for this purpose which is adapted to control a flow of liquid from the source of supply to the supply tank in a manner such as to maintain a substantially uniform level of liquid in the supply tank at all times. Provision is also made in the preferred embodiment of the invention for maintaining a relatively high column of liquid above 40 the liquid control valve at the start of each cycle of operation providing a consistently uniform head of liquid above the valve for successive filling operations whereby to enable rapid starting of the flow of liquid upon opening of the valve to perform the filling operation.

In accordance with still another feature of the invention, novel timing mechanism is provided for controlling the opening and closing of the liquid control valve where-

by the amount of liquid permitted to flow into successive containers may be accurately controlled. The present timing mechanism is preferably provided with pneumatic controls arranged to initiate operation of the timing mechanism upon elevation of the containers into filling position to effect opening of the liquid control valve and to start the flow of liquid into the containers, and after a predetermined and accurately controlled interval of time the liquid control valve is arranged to be gradually closed as it approaches the end of the filling cycle. Provision is also made for adjustably varying the timing of the filling cycle whereby to permit variation of the filling height and to accommodate different size containers.

Referring now to the drawings and particularly to Figs. 1 and 2, in general the present gravity type filling machine is illustrated as embodied in a semi-automatic type of machine wherein the containers 10 are supported on an elevating platform 12 in alignment with their respective filling heads indicated generally at 14 and manually elevated into operative relation to the filling heads to receive the liquid discharged from the filling head nozzles. In general the container supporting and elevating means may take the form of the supporting and elevating mechanism shown in the United States patent to Pennock, No. 1,737,677, wherein the containers are moved by a conveyor 11 onto the supporting platform 12 which is mounted on a slide 15 arranged for reciprocation in a bracket 16 forming a part of the machine frame. As herein shown, a lever 18 pivotally mounted at 20 in the bracket 16 is provided with a handle 22 at one end and with a counterweight 13 at the other end thereof, the lever being connected to the slide 15 by a link 24, thus forming a toggle for elevating the containers into operative relation to the filling heads 14. As indicated at 17, suitable adjustable stop means may be provided at the end of the slide 15 for engagement with the lower end of the bracket 16 to bring the supporting platform to rest at the preselected height.

As herein illustrated, the filling heads 14 are adjustably supported in an elongated slot formed in a horizontal bracket 26 connected to brackets 27 extending from a supporting slide 28 mounted for vertical adjustment in a grooved portion 30 of a frame member 32. The supporting slide 28 is arranged to be manually adjusted through connections including a threaded member 34 connected to the lower end of the slide 28. The threaded portion of the member 34 extends through a bevelled gear 36 supported from the machine frame, and a bevelled gear 38 meshing with the gear 36 is fast on a horizontal shaft 40 provided with a handle 42 for effecting manual rotation of the gear in a manner similar to that shown in the Pennock patent above referred to. Each filling head 14 is provided with an inlet 44 connected by a flexible tube 46 to the lower end of a supply tank 48, and as illustrated in Fig. 2, the tank 48 may be supported by a bracket 50 connected to the supporting slide member 28 so that in operation the supply tank together with the filling nozzles may be vertically adjusted to accommodate various heights and sizes of containers.

Referring now to Figs. 7 and 8, the filling head 14 therein shown includes a hollow member 52 provided with a chamber 54, one side of the chamber communicating with the inlet 44. The lower end of the member 52 is provided with a cylindrical extension 56 adapted to receive a nozzle 58 threadedly secured thereto as shown. The liquid control valve includes a valve member 60 supported at the lower end of an elongated rod 62 connected at its upper end by a link 64 to an arm 66 fast on a rocker shaft 68 journaled in brackets 70 supported by an extension from the bracket 27, as shown in Fig. 2. The valve member 60 may be generally of "acorn" shape, as illustrated, pointed at its lower end and provided with a grooved portion 72 adjacent its upper and larger diam-

eter end into which a resilient ring 74 is placed. The resilient ring 74 may comprise rubber or rubber-like material, and the outer periphery of the resilient ring extends beyond the periphery of the body of the valve member 60 as shown. The valve member 60 is arranged to cooperate with the cylindrical wall of an opening 76 formed in the member 52 immediately below the larger diameter chamber 54, the opening 76 being of slightly smaller diameter than the outer periphery of the resilient ring 74. The diameter of the opening 55 in the cylindrical extension 56 immediately below the opening 76 is preferably enlarged to provide clearance for vertical movement of the valve member 60. In operation when the valve member 60 is elevated into engagement with the cylindrical wall of opening 76, the annular ring 74 is arranged to be slightly compressed to cut off the flow of the liquid passing through the filling head, and upon a slight further upward movement of the valve member 60, a suction will be created in the nozzle portion 58 of the filling head to prevent dripping of liquid from the nozzle upon completion of the filling operation. The nozzle 58 illustrated in Fig. 7 is of a relatively large diameter, and in practice a screen 78 may preferably be placed at the discharge end of the nozzle to provide a sufficient surface tension area to assist in retaining the liquid within the nozzle when a relatively large diameter nozzle is employed. As illustrated in Fig. 9, when a relatively small diameter nozzle 79 is used the screen 78 may be eliminated.

The upper portion of the hollow member 52 may be provided with an elongated outer tubular extension 80 provided with a cap member 82 having an opening through which the valve rod 62 extends. An inner elongated tubular member 84 extending from the chamber 54 in the member 52 forms a reservoir for the liquid entering the chamber 54 when the valve member 60 is closed, the liquid entering the chamber and rising to a predetermined level equal to the level of the liquid in the supply tank 48 whereby to provide a hydrostatic head of liquid immediately above the valve to assist in starting the flow through the nozzle when the valve is opened. As illustrated in Figs. 7 and 8, the rod 62 is provided with a collar 86 having relatively small pins 88 extending radially therefrom into sliding engagement with the interior wall of the inner tube 84 to form a centering guide for the valve member 60.

Provision is made for operating the movable valve member 60 to effect opening and closing of the valve in a predetermined interval of time, and as illustrated in Fig. 2, the rocker shaft 68 is provided with a lever 67 fast thereon and connected to a pneumatically operated plunger 90 forming a part of an air cylinder 92 arranged to be actuated to effect elevation of the plunger 90 to open the valve 60 and start the filling operation upon elevation of the containers into operative relation to the nozzles 14, and after a predetermined interval of time to cause descent of the plunger 90 to effect elevation of the valve member 60 and cut off the supply of liquid. As illustrated in detail in Figs. 10 and 11, the air cylinder 92 is provided at its lower end with a slide valve 94 normally maintained in the position shown in Fig. 11 by a spring 96 in which position a passageway 98 in the slide valve is aligned with a passageway 100 formed in the cylinder, the passageway 100 communicating with passageways 102, 104, 105 and 106 leading into the upper end of the cylinder chamber 108 in which a piston 110 formed at the end of the plunger 90 is vertically movable. When the passageways are thus aligned, as shown in Fig. 11, downward movement of the plunger 90 and upward rocking of the valve member 60 is effected, thus closing the valve 60. During such downward movement of the plunger 90 the air below the piston 110 is permitted to escape through passageways 112, 114, 116 into the slide valve chamber 117 from which the air may escape to

the atmosphere through a passageway 118, as shown. The passageway 98 is connected to a source of compressed air by a pipe 99 for effecting movement of the plunger 90, and the slide valve chamber 117 is connected by a pipe 101 to a source of compressed air for effecting movement of the slide valve 94 to the right, as illustrated in Fig. 10. When thus moved to the right, the passageway 98 in the slide valve is aligned with a central passageway 120 formed in the cylinder which communicates with the underside of the piston 110 in the chamber 108, thus effecting upward movement of the plunger 90 to rock the valve member 60 downwardly and effect opening of the liquid control valve 60. The air above the piston 110 is permitted at this time to escape through passageways 106, 105, 104, 102 and 100, the passageway 100 communicating with a passageway 122 formed in the slide valve 94 which in turn communicates with an atmospheric opening 124, as shown. From the description thus far it will be observed that through the connections described the pneumatically operated plunger 90 is arranged to be raised and lowered to effect opening and closing of the liquid control valve 60.

As diagrammatically illustrated in Fig. 14, provision is made for automatically controlling the operation of the air cylinder 92 to effect opening of the valve 60 when the containers are elevated into operative relation to the filling heads 14, and after a predetermined interval of time to effect reversal of operation of the air cylinder 92 and closing of the valve 60. As herein shown, the air cylinder 92 forms part of a compressed air line having a source of compressed air, such as an air compressor, diagrammatically indicated at 126, which is connected through the usual filter 128, air gauge 130 and shutoff valve 132 to a branch air line 134. The air line 134 may be provided with a conventional air regulator 136 and a lubricator 138 and is connected by an air line 140 through a cam operated control valve 142 and a normally open manually controlled valve 144 to the pipe 101 communicating with the slide valve chamber 117 of the air cylinder 92. The cam operated valve 142, as shown in Figs. 4 and 15, may comprise a cylindrical disk 145 mounted to rock in a casing 146 provided with inlet and outlet passageways 148, 150 respectively for connection to the air line 140, the disk 145 having a through port 152 arranged in alignment with the passageways 148, 150 when the disk is rocked into one position of operation, as shown in Fig. 5, to permit air to pass through the line 140 to the valve chamber 117 of the air cylinder 92. The disk 145 is also provided with a second passageway 154 arranged to be aligned with the inlet passageway 148 and which extends radially through the periphery of the disk for alignment with an atmospheric passageway 156 formed in the casing 146 when the disk 145 is rocked into another position of operation, as indicated in Fig. 6. As herein shown, the disk 145 is provided with a T-shaped extension 158 having a cam roll 160 at one end of the T for cooperation with a cam 162 fast on a one revolution cam shaft 164 supported in bearings 166 attached to the base 168 of the machine frame, as shown in Fig. 1. The other end of the T is provided with a rod 170 slidingly extended through an opening in a bracket 172. A spring 174 coiled about the rod and interposed between a collar 175 fast on the rod and a washer bearing against the inner face of the bracket 172 serves to rock the disk 145 in a counterclockwise direction, as shown in Fig. 6, to align the passageway 154 with the atmospheric opening 156, the cam operating to rock the disk clockwise to align the through port 152 with the air lines 140.

As diagrammatically indicated in Fig. 14, when the valve 142 is opened to permit air to pass through lines 140 and 101, the slide valve 94 is moved to the right, as shown in Fig. 10, to align passageway 98 with a source of compressed air through pipe 99 to effect elevation of the plunger 90. As herein shown, the pipe 99 is con-

nected to a second branch air line 135 also provided with a conventional air regulator 137 and lubricator 139, as shown in Fig. 14.

As illustrated in Fig. 1, the one revolution cam shaft 164 is arranged to be rotated through connections from a motor 176 which drives the input shaft 178 of a commercially available variable speed hydraulic transmission unit 180. The output shaft of the transmission unit 180 is connected to a gear reduction unit 182 which in turn is connected by a belt and pulley drive 184 to the driving element of a conventional one revolution clutch 185 mounted on the cam shaft 164. As illustrated in Fig. 16, the driven element of the one revolution clutch 185 is arranged to be disengaged from the driving element thereof by a latch arm 186 pivotally mounted at 188 in a bracket 190 attached to the base of the machine, the latch arm being provided with a cutout portion 192 arranged to engage a pin 194 carried by the driven element to effect disengagement of the clutch. A spring 196 is arranged to rock the latch arm in a clockwise direction viewing Fig. 16, and the free end of the arm is arranged to bear against the plunger 198 of a pneumatically operated clutch trip valve 200. The valve 200 is connected in a branch air line 202 which also includes a normally closed pilot valve 204 arranged to be opened upon elevation of the container supporting platform 12, and a standard flow control valve 206, as shown in Fig. 14. The plunger 198 may be spring urged downwardly, and when the pilot valve 204 is opened the plunger is elevated to rock the arm 186 counterclockwise to permit engagement of the clutch to start a cycle of operation, the arm 186 immediately returning to its initial position to effect disengagement of the clutch at the end of one revolution. A second latching arm 208 also pivotally mounted at 188 and having a spring 210 for urging the arm in a clockwise direction is provided with a roller 212 arranged to engage a cutout portion in a disk 214 fast on the cam shaft 164 for effecting stopping of the cam shaft in the same radial position at the end of each cycle of operation. As shown in Fig. 17 and in dot and dash lines in Fig. 16, the free end of the arm 208 is provided with a set screw 216 arranged to be engaged by the free end of the latch arm 186 when the latter is urged upwardly by the clutch trip plunger 198 to raise the roller 212 out of locking engagement with the disk 214 at the same time the clutch is permitted to become engaged.

As above described, the valve 204 connected in the branch air line 202 is arranged to be opened upon elevation of the supporting platform 12 to bring the containers into operative position to their respective filling heads 14. As indicated generally in Fig. 1 and in detail in Fig. 3, the valve 204 may comprise a rotary disk type of valve, similar to that shown in Fig. 4, provided with ports arranged to permit passage of air therethrough when rocked in a clockwise direction viewing Fig. 3 and to vent the air line to the atmosphere when rocked in a counterclockwise direction. The valve 204 is mounted on a bracket 218 attached to the machine frame, and a spring 220 connected to one end of the T-shaped extension from the rotary disk is arranged to urge the valve into a closed position. The other end of the T-shaped extension is provided with a roller 224 arranged to be engaged by a trip latch 226 pivotally mounted at 228 in an extension 230 carried by and movable with the supporting platform 12, as shown in Fig. 3. The latch 226 is provided with an offset portion 232 carrying a stud 234, one end of which engages the underside of the extension to limit the rocking movement of the latch in a clockwise direction. The other end of the stud is provided with a spring 236 connected to the extension which permits counterclockwise rocking of the latch 226 upon downward movement of the supporting platform 12 and engagement with the roller so as to enable the latch

to pass the roller and return to its initial position during its descending movement.

In the operation of the filling machine thus far described, it will be observed that when the supporting platform 12 is elevated to present the containers into operative relation to the filling heads 14, the latch 226 carried by the supporting platform 12 effects tripping of the valve 204 to open the same, thereby effecting elevation of the plunger 198 of the clutch trip valve 200 to permit engagement of the clutch and start rotation of the one revolution shaft 164. The cam 162 then effects opening of the valve 142 to cause shifting of the slide valve 94 to the right, as shown in Fig. 10, permitting compressed air to enter from line 99 to effect elevation of the plunger 90 and downward opening of the valve member 60 to start the flow of liquid through the filling nozzles into the containers. After a predetermined and selected interval of time, determined by the rate of speed of the one revolution cam shaft, the cam 162 effects closing of the valve 142, thus permitting movement of the slide valve 94 to the left, as shown in Fig. 11, permitting compressed air from line 99 to cause descent of the plunger 90 and effecting upward closing of the liquid control valve 60. Thereafter, the one revolution shaft 164 is disengaged by the latch arm 186 at the end of its one revolution, and the latch arm 208 effects locking of the shaft in a predetermined position preparatory to the start of another cycle of operation. The normally open manually controlled valve 144 may be similar in structure to the valve 142 and is provided as a safety valve to permit manual control to prevent the flow of liquid when no container is present; or to discontinue the flow into a broken or misaligned container.

It will be understood from the description thus far that the rate of speed of the cam shaft 164 which controls the timing of the filling operation may be quickly and easily varied to obtain the exact filling time required by adjustment of the hydraulic variable speed transmission unit 180. As shown in Fig. 1, the variable speed unit 180 may be provided with a control knob 181 to vary the speed of the output shaft thereof to either increase or decrease the filling time to obtain the exact filling height required in the containers.

In practice it was found that a rapid opening of the liquid control valve 60 and a relatively slow closing of the valve is conducive to most efficient filling operation. In operation when the valve 60 is opened, the liquid accumulated in the tube 84 above the chamber 54 in the filling head 14 effects rapid starting of the filling operation. The cam 162 which controls the valve 60 may be designed to effect rapid opening of the air valve 142 and shifting of slide valve 94 to permit the full pressure of air line 99 to enter the air cylinder 92 and effect rapid opening of the valve 60 at the start of the filling operation. Thereafter, as the cam shaft 164 approaches the end of the filling time, the cam 162 may be designed to effect relatively slow closing of the valve 142 and slow shifting of the slide valve 94 so that reversal of operation of the air cylinder 92 is accomplished relatively slowly by an initial reduced air pressure from air line 99. As above described, gradual closing of the valve 60 effects a minimum disturbance of the liquid when approaching the filling height in the container which is conducive to accurate filling operation, and a slight continued upward movement of the valve member after closing off the flow of the liquid through the nozzle effects a slight suction to retain the column of liquid remaining below the valve member within the nozzle so as to prevent dripping therefrom and to thus enable exact amounts of liquid to be measured into successive containers each filling operation.

It will be observed that in the operation of the present liquid control valve 60 both the opening and the closing movements of the valve are positively controlled and

that closing of the valve with an upward stroke tends to taper off the flow gradually for accurate filling operation. While the movable valve member 60 may obviously comprise an all-rubber plug or a plug of other resilient material, such as synthetic rubber, the disclosed structure embodying an annular resilient member supported in a grooved portion of the rigid body of the valve provides a relatively simple and economical structure of manufacture and may be easily and economically replaced when worn.

In accordance with another feature of the present invention conducive to accurate filling operation, novel provision is made for maintaining a substantially uniform level of liquid in the supply tank at all times whereby to produce a substantially constant hydrostatic head of liquid therein to maintain a uniform pressure flow of liquid to the filling heads during the filling operation. As illustrated in Fig. 1, the supply tank 48 is arranged to receive liquid from a main supply thereof through a pipe 250 having a valve 252 arranged to be opened upon a slight lowering of the level of the liquid in the tank 48 from a predetermined level and to be closed when said predetermined level is reached. The valve 252 is preferably arranged to be actuated through pneumatically operated control means, and as herein shown, a float 254 guided for vertical movement in the tank 48 is provided with a valve member 256 arranged to cooperate with an air jet 258 forming a part of the pneumatic control mechanism. As shown in detail in Fig. 13, the air jet 258 is secured in a block 260 having a chamber 262 provided with an inlet 264 having a restricted throat portion 266, the air jet having a passageway provided with a restricted orifice 268 through which the air is discharged. As indicated in Fig. 14, the inlet 264 to the chamber 262 is connected in the compressed air line 135, and the chamber 262 is also provided with an intermediate passageway 270 connected by a pipe 272 to a pilot valve 274. The pilot valve 274 is connected in a compressed air line 276 from the branch line 135 to the slide valve chamber of an air cylinder 278 which may and preferably will comprise an air cylinder of the type shown in Figs. 10 and 11 except that it may be inverted, as indicated in Fig. 12. The piston rod or plunger 280 of the air cylinder 278 may be connected to one end of a rocker arm 282 pivotally mounted at 284 in a bracket extended from the valve housing 252. The other end of the rocker arm 282 is connected by a pin and slot connection 285 and to rod 287 to the valve member 286 which is vertically movable in a chamber 288 formed in the housing and in communication with passageways 291, 293 forming a continuation of the inlet pipe 250. The valve member 286 is provided with an opening 290 arranged to be aligned with the inlet passageways in one position of operation, and in another position of operation the valve member is arranged to cut off the flow of liquid through the pipe 250. The air cylinder 278 is connected to a compressed air line 292 forming a branch of line 134, as diagrammatically shown in Fig. 14.

In the operation of the liquid level control mechanism above described, the pilot valve 274 is normally spring closed to prevent passage of compressed air to the slide valve chamber of air cylinder 278 so that the slide valve of air cylinder 278 is aligned with passageways similar to those shown in Fig. 11 except that the air cylinder is inverted to effect upward movement of the piston rod 280 and downward movement of the valve rod 287, thus opening the valve 286 to permit the flow of liquid through the inlet pipe into the tank 48. When the level of the liquid in the tank approaches the predetermined level the valve member 256 will be raised by the float 254 into proximity to the discharge orifice 268 of the air jet 258, thus impeding the discharge of air therethrough and effecting a substantial increase in the pressure in the chamber 262 sufficient to effect opening of

the pilot valve 274. The compressed air in line 276 is thus permitted to effect shifting of the slide valve in air cylinder 278 to align the passageways in a manner similar to that shown in Fig. 10 except that the air cylinder is inverted to effect downward movement of the piston rod 280 and upward movement of the valve member 286 to close off the flow of liquid into the supply tank 48. It will be understood that in practice the valve member 256 is normally spaced a short distance from the jet orifice 268 and that a relatively small increment of movement toward the jet orifice will effect a substantial increase in the pressure in the chamber 262 to effect closing of the inlet valve, and that a relatively small downward movement of the valve member 256 when the level of the liquid is lowered by withdrawal therefrom during the filling operation will substantially reduce the pressure in the chamber 262 to permit full opening of the inlet valve 286 whereby to maintain a substantially constant predetermined level of liquid in the supply tank 48. In other words the illustrated valve structure will immediately sense a relatively small withdrawal of liquid to effect full opening of the valve 286 to quickly replace the withdrawn liquid so as to maintain a substantially constant hydrostatic head of liquid and pressure flow through the filling heads which is conducive to rapid, accurate and efficient filling operation.

As illustrated in Fig. 2, the upwardly extended tubular portions 80, 84 of the filling heads 14 preferably extend above the predetermined filling level of the liquid in the tank 48, as indicated at 300, so that in operation the liquid entering the filling head chamber 54 when the valve 60 is closed will rise in the inner tubular member 84 until it reaches a height equal to the level of the liquid in the tank 48 to provide a head of liquid above the valve 60 sufficient to effect rapid starting of the filling operation, as described, when the valve 60 is opened.

As illustrated in Fig. 1, a plurality of containers are simultaneously filled in the manner herein described, one air cylinder 92 being provided for all of the filling heads to effect simultaneous opening and closing of all of the liquid control valves 60. As herein shown, the lever 67 fast on the rocker shaft 68 is connected to the plunger 90 of the air cylinder 92, and the arms 66 also fast on the rocker shaft are connected to the individual valve rods 62. In practice each filling head is carefully constructed to maintain close tolerances in dimensions so that the passageways and nozzle diameters of each head will be substantially the same whereby in operation each filling head will respond to the control mechanism in a similar manner to provide accurate amounts of liquid in each container. However, in the event that there is any slight variation in amount in the different containers, vertical adjustment of the inner tubular member 84 to present the lower end thereof in the path of the inlet 44 and in a manner such as to partially restrict the flow through the inlet 44 is effective to slightly reduce the amount of liquid delivered to a particular container whereby to provide equal amounts in each container.

From the above description it will be observed that the present structure of gravity type filling machine is capable of producing accurately filled containers by the coaction of the novel positively operated liquid control valve; accurate and adjustably variable timing mechanism for controlling the opening and closing of the control valve; and quick acting and efficient constant level control mechanism for maintaining a substantially uniform hydrostatic head in the supply tank for controlling the rate of flow of the liquid to the filling heads.

While the preferred embodiment of the invention has been herein illustrated and described, it will be understood that the invention may be embodied in other forms within the scope of the following claims.

Having thus described the invention, what is claimed is:

1. In a container filling machine of the character described, a filling head having a chamber provided with an inlet and a cylindrical outlet, a liquid control valve comprising a vertically movable valve member having a sealing element of resilient material for cooperation with a portion of said cylindrical outlet, said outlet portion being elongated and of a uniform and slightly smaller diameter than said valve member, the walls of said outlet portion forming a continuous seat for said valve member, said resilient sealing element of the valve member being slightly compressed when moved upwardly beyond the end of and into sliding engagement with the walls of said reduced diameter seat portion to close the valve, the sealing element of the valve member being movable within the walls of said reduced diameter portion.
2. In a container filling machine of the character described, a filling head having a chamber provided with an inlet, a cylindrical outlet having a portion of reduced diameter and a filling nozzle extended from said outlet, a liquid control valve comprising a vertically movable valve member having a sealing element of resilient material for cooperation with said reduced diameter portion of said outlet forming a seat therefor, said reduced diameter portion being elongated and of uniform diameter, said resilient sealing element of the valve member being slightly compressed when moved upwardly beyond the lower end of and into sliding engagement with the walls of said reduced diameter seat portion to close the valve seat, continued upward movement of the compressed sealing element of the valve member within the reduced diameter portion creating a suction in said extended nozzle portion below the valve member whereby to prevent dripping from the nozzle at the end of a filling operation.
3. A filling machine as defined in claim 2 wherein the movable valve member comprises a rigid material having an annular resilient portion for cooperation with the walls of said reduced diameter seating portion.
4. A filling machine as defined in claim 2 which includes a liquid supply wherein the chamber is also provided with an elongated hollow upward extension open to the atmosphere and into which the supply liquid will rise to the supply level when the valve is closed to form a column of liquid above the valve to assist in effecting a rapid start of the flow when the valve is opened.
5. In a container filling machine of the character described, a filling head having a chamber provided with an inlet and a cylindrical outlet and a filling nozzle extended from said outlet having a portion of reduced diameter, a liquid control valve comprising a vertically movable valve member provided with an annular groove, a resilient ring disposed in said groove for cooperation with the walls of said reduced diameter portion of said outlet, said reduced diameter portion being elongated and of uniform diameter, the walls thereof forming a continuous seat for said resilient ring, said resilient ring being slightly compressed when the resilient ring of the valve member is moved upwardly beyond the lower end of and into sliding engagement with the walls of said reduced diameter seat portion to close the valve, continued upward movement of the valve member within the reduced diameter portion creating a suction in said extended nozzle portion below the valve member whereby to prevent dripping from the nozzle at the end of a filling operation.
6. A filling machine as defined in claim 5 wherein the outlet includes an enlarged diameter clearance space for said valve member between the reduced diameter seat portion and said nozzle.
7. In a container filling machine of the character described, a liquid supply having a predetermined liquid level, a filling head having a chamber provided with a liquid supply inlet operatively connected to said liquid

supply and having a discharge outlet, a liquid control valve cooperating with said outlet, said chamber also having an elongated upward extension open to the atmosphere and into which the liquid will flow from the liquid supply when the valve is closed and forming a reservoir for a column of liquid above the chamber and the valve corresponding to the supply level to assist in effecting a rapid start of the flow when the valve is opened.

8. In a container filling machine of the character described, a liquid supply having a predetermined liquid level, a filling head having a chamber provided with a liquid supply inlet operatively connected to said liquid supply and having a discharge outlet, a liquid control valve cooperating with said outlet, said chamber also having an elongated upward extension open to the atmosphere and into which the liquid will flow from the liquid supply when the valve is closed and forming a reservoir for a column of liquid above the chamber and the valve corresponding to said predetermined level to assist in effecting a rapid start of the flow when the valve is opened, said extension containing a member mounted for vertical movement in said chamber relative to said liquid supply inlet, and means for adjusting said member relative to the liquid supply inlet, whereby to vary the rate of flow through said supply inlet.

9. In a container filling machine of the character described, a liquid supply tank having a predetermined liquid level, a filling head having a chamber provided with an inlet and an outlet operatively connected to and disposed below the level of the liquid in the supply tank, a liquid control valve cooperating with said outlet, said chamber also having an elongated upward extension open to the atmosphere and into which the liquid will rise when the valve is closed to the predetermined level of the liquid in the supply tank forming a reservoir for a column of liquid directly above the chamber and the valve to assist in effecting a rapid start of the flow of liquid when the valve is opened.

10. In a container filling machine of the character described, a filling head having a chamber provided with an inlet, a cylindrical outlet having a portion of reduced diameter and a filling nozzle extended from said outlet, a liquid control valve comprising a vertically movable valve member having a sealing element of resilient material for cooperation with the walls of said reduced diameter portion of said outlet forming a seat therefor, said outlet being elongated and of uniform diameter and providing a continuous seat for the valve member, said resilient sealing element of the valve member being slightly compressed when moved upwardly beyond the end of and into sliding engagement with said reduced diameter seat portion to close the valve, continued upward movement of the sealing element of the valve member within the reduced diameter portion creating a suction in said extended nozzle portion to prevent dripping from the nozzle at the end of a filling operation, and means for opening and closing said valve member independently of container cooperation including means for controlling the valve movement to effect a rapid opening and a relatively slow closing movement whereby to taper off the flow and effect a minimum disturbance of the liquid during the closing movement.

11. In a container filling machine of the character described, a filling head having a chamber provided with an inlet, a cylindrical outlet having a portion of reduced diameter and a filling nozzle extended from said outlet, a liquid control valve comprising a vertically movable valve member having a sealing element of resilient material for cooperation with the walls of said reduced diameter portion of said outlet forming a continuous seat therefor, said resilient sealing element of the valve member being slightly compressed when moved upwardly beyond the end of and into sliding engagement with the walls of said reduced diameter seat portion to close the

valve, continued upward movement of the sealing element of the valve member within the reduced diameter portion creating a suction in said extended nozzle portion to prevent dripping from the nozzle at the end of a filling operation, means operated independently of container cooperation for opening and closing said valve member including means for controlling the valve movement to effect a rapid opening and a relatively slow closing movement whereby to taper off the flow and effect a minimum disturbance of the liquid during the closing movement, liquid supply means for providing a uniform pressure and velocity of flow of liquid through said filling nozzle, and means for controlling the filling time to provide uniform amounts of liquid in successive containers.

12. A filling machine as defined in claim 11 wherein the means for controlling the filling time includes a one revolution clutch, and adjustably variable driving means connected to said one revolution clutch for varying said filling time.

13. A filling machine as defined in claim 12 wherein the container is supported on a platform for elevating the container into operative filling position to the filling head, said control means including means actuated by said elevating platform for initiating operation of said one revolution clutch.

14. A filling machine as defined in claim 13 wherein the control means comprises a pneumatic system including an air cylinder operatively connected to said liquid control valve, and a cam operated valve in said system for controlling the operation of said air cylinder to effect said rapid opening and relatively slow closing movement of the liquid control valve.

15. A filling machine as defined in claim 14 which includes a manually operated valve in said system for effecting closing of the liquid control valve independently of said cam operated valve.

16. In a container filling machine of the character described, a liquid supply, a filling head having a chamber provided with a liquid supply inlet operatively connected to the supply and a discharge outlet, a liquid control valve cooperating with said outlet, said liquid supply including means for maintaining a uniform pressure and velocity of flow of liquid through said filling head whereby to produce a stream of predetermined volume per unit of time, means for supporting a container in operative and non-sealing relation to said discharge outlet, and means operated independently of container cooperation and independently of the weight of the liquid in the container for opening and closing said liquid control valve including pneumatically operated control means operatively connected to the valve for controlling the filling and a timer controlling said control means to provide uniform amounts of liquid in successive containers and including means for effecting a rapid opening and a relatively slow closing movement of the valve whereby to taper off the flow and effect a minimum disturbance of the liquid during the closing movement.

17. In a container filling machine of the character described, a liquid supply tank, a filling head having a chamber provided with an inlet and an outlet operatively connected to the supply tank, a liquid control valve cooperating with said outlet, means for maintaining a substantially constant predetermined level of liquid in said supply tank during the filling operation including a supply valve, a float in said tank, and pneumatically operated means controlled by said float and operatively connected to said supply valve for effecting full opening of said supply valve upon a relatively small withdrawal of liquid and a correspondingly small lowering of said predetermined level and full closing of said supply valve upon a correspondingly small addition of liquid and return to said predetermined level whereby

to maintain a substantially constant hydrostatic head of liquid in the tank during the filling operation, said pneumatically controlled means including means for effecting a rapid increase or decrease in air pressure for actuating said supply valve upon a relatively small movement of said float.

18. In a container filling machine of the character described, a liquid supply tank, a filling head having a chamber provided with an inlet and an outlet operatively connected to the supply tank, a liquid control valve cooperating with said outlet, means for maintaining a substantially constant predetermined level of liquid in said supply tank during the filling operation including a supply valve, a float in said tank, and means controlled by said float and operatively connected to said supply valve for effecting full opening of said supply valve upon a relatively small withdrawal of liquid and lowering of said predetermined level whereby to maintain a substantially constant hydrostatic head of liquid in the tank during the filling operation, said float controlled means including a pneumatically operated control unit having an air chamber provided with a restricted throat for conducting air under pressure to said air chamber, said air chamber being provided with a small discharge orifice, means connected to and movable with said float cooperating with said orifice to control the escape of air therefrom to vary the pressure in said chamber in response to minute movement of said float, a pilot valve responsive to variations in pressure in said air chamber, and an air cylinder controlled by said pilot valve and operatively connected with and controlling the operation of said supply valve.

19. In a container filling machine of the character described, a filling head having a chamber provided with an inlet, an outlet and a filling nozzle extended from said outlet, a liquid control valve comprising a vertically movable valve member of resilient material for cooperation with a reduced portion of said outlet forming a seat therefor, said resilient valve member being slightly compressed when moved upwardly into engagement with said reduced outlet portion to close the valve and creating a suction in said extended nozzle portion to prevent dripping from the nozzle at the end of a filling operation, a liquid supply tank operatively connected to said inlet, means for maintaining a substantially constant predetermined level of liquid in said supply tank during the filling operation including a supply valve, and float controlled means operatively connected to said supply valve adapted to control the operation of the supply valve to effect full opening or closing thereof upon minute deviations from said predetermined level.

20. In a container filling machine of the character described, a supply tank, a filling head having a chamber provided with an inlet operatively connected to the supply tank, an outlet and a filling nozzle extended from said outlet, a liquid control valve in said filling head comprising a vertically movable valve member having a resilient portion cooperating with a reduced diameter portion of said outlet forming a seat therefor, said resilient portion being slightly compressed when the valve is moved upwardly into engagement with the reduced diameter outlet to close the valve and creating a suction in said extended nozzle portion at the end of the filling operation, means for maintaining a substantially constant predetermined level of liquid in said supply tank during the filling operation including a supply valve, and float controlled means operatively connected to said supply valve adapted to control the operation of the same to effect full opening or closing of the valve upon minute deviations from said predetermined level, and means for opening and closing said filling head valve including control means operatively connected to said filling head valve for controlling the filling time and for effecting a rapid opening and a relatively slow closing movement of the filling head valve.

21. In a container filling machine of the character described, a filling head having a chamber provided with an inlet and an outlet, said outlet being elongated and of uniform diameter, a liquid control valve having a sealing element mounted for sliding movement within said outlet and in sealing engagement with the walls thereof providing an elongated, continuous seat for said valve, means for moving the sealing element of the valve downwardly out of engagement with the walls of the outlet into an open position to permit liquid to flow from the chamber through the outlet to be discharged therefrom, and for thereafter moving the sealing element of the valve upwardly into and within said outlet beyond the lower end thereof to thereby create a suction in the portion of the outlet below the sealing element of the valve whereby to retain any liquid therein and prevent dripping from the nozzle at the end of a filling operation.
